CLAIM

The ornamental design for a vertical fluorescent light fixture, as shown and described.

DESCRIPTION

FIG. 1 is a perspective view of the vertical fluorescent light fixture, according to the new and unique ornamental design;

FIG. 2 is a right side view of the vertical fluorescent light fixture as shown in FIG. 1 further showing the new design, with the left side being a mirror image thereof;

FIG. 3 is a front view of the reflector for horticulture lighting as shown in FIG. 1 further showing the new design, with the back side being a mirror image thereof;

FIG. 4 is a top view of the reflector for horticulture lighting as shown in FIG. 1 further showing the new design; and,

FIG. 5 is a bottom view of the reflector for horticulture lighting as shown in FIG. 1 further showing the new design.
